CLAIM

The ornamental design for a bottle with cap, as shown and described.

DESCRIPTION

FIG. 1 is a front, top, and side perspective view of a bottle with cap embodying my new design;

FIG. 2 is a side elevational view thereof;

FIG. 3 is a rear elevational view thereof;

FIG. 4 is a top plan view thereof;

FIG. 5 is a front, top, and side perspective view of the bottle with cap of FIG. 1 with the cap removed so as to show the portion of the bottle beneath the cap; and,

FIG. 6 is a front, top, and side perspective view of the cap portion of the bottle with cap of FIG. 1, shown separately for ease of illustration.
